UNITED STATES PATENT OFFICE.

ROBERT G. WAGNER AND ERNEST J. SCHWEITZER, OF LOS ANGELES, CALIFORNIA.

DESIGN FOR A BOWL FOR A LIGHTING-FIXTURE.

49,130.

Specification for Design.

Patented May 30, 1916.

Application filed March 22, 1916. Serial No. 86,007. Term of patent 3½ years.

To all whom it may concern:

Be it known that we, ROBERT G. WAGNER and ERNEST J. SCHWEITZER, citizens of the United States, residing at Los Angeles, in the county of Los Angeles and State of California, have invented a new, original, and ornamental Design for a Bowl for a Lighting-Fixture, of which the following is a specification, reference being had to the accompanying drawing, forming part thereof.

The figure is a side elevation of the bowl.

We claim:

The ornamental design for a bowl for a lighting fixture as shown.

In witness that we claim the foregoing, we have hereunto subscribed our names this 13th day of March, 1916.

ROBERT G. WAGNER.

ERNEST J. SCHWEITZER.

Witnesses:

L. R. WHARTON,

W. W. PHELPS.
